CLAIM

The ornamental design for a media device, as shown and described.

DESCRIPTION

FIG. 1 is a front perspective view of a media device showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken line showing of the environmental structure in FIGS. 3–7 is for illustrative purposes and forms no part of the claimed design.
